UNITED STATES PATENT OFFICE.

WILLIAM C. FARNUM, OF ARLINGTON, VERMONT, ASSIGNOR TO WYCKOFF, SEAMANS & BENEDICT, OF ILION, NEW YORK, A CORPORATION OF NEW YORK.

TYPE-WRITING MACHINE.

No. 904,055.

Specification of Letters Patent.

Patented Nov. 17, 1908.

Application filed March 21, 1903. Serial No. 148,942.

To all whom it may concern:

Be it known that I, WILLIAM C. FARNUM, citizen of the United States, and resident of Arlington, in the county of Bennington and State of Vermont, have invented certain new and useful Improvements in Type-Writing Machines, of which the following is a specification.

This invention relates to improvements in the carriage-feed mechanism of typewriting machines, including visible-writing machines and understrike or swinging-carriage machines, in which the carriage-feed mechanism comprises a rack and pinion that are or may be constantly engaged with each other, one object of the invention being to render pinion-controlling mechanism, embodying a feed-wheel and feed-dogs, operative by means of a release-key on the carriage, to release the feed-wheel from the control of the dogs, and another object of the invention being to enable the carriage of an understrike machine to be readily moved from right to left, unobstructed by the feed-mechanism, when the platen is in an elevated position.

The invention consists of various features of construction, combinations and arrangements of parts, all of which are hereinafter fully described and particularly defined in the appended claims.

In the accompanying drawings, in which like reference numerals designate like parts in the different views, Figure 1 is a front to rear vertical section and elevation showing certain parts of a swinging-carriage type-writing machine embodying the invention; Fig. 2, a vertical section of the carriage, platen and certain other parts, the platen being shown in an elevated position; Fig. 3, a rear elevation of the frame, and sectional elevation of the feed-mechanism, of the machine; Fig. 4, a broken front elevation on an enlarged scale of parts shown in Fig. 2, with other parts of the feed-mechanism, the platen being shown elevated; Fig. 5, a plan of parts of the feed-mechanism and fragment of the top of the frame of the machine; and Fig. 6, a rear sectional elevation thereof.

The mechanism herein described and claimed in combination with a swinging-paper carriage is especially useful in connection with a printing-point indicator, which,

inasmuch as it is a well-known device, is not shown in the drawings of this application. 55

The invention is shown for convenience applied to a machine differing from the common No. 6 Remington only with respect to the carriage-feed mechanism, but is applicable also to other understrike or swinging-carriage machines, while certain parts of the invention are applicable alike to swinging-carriage and visible-writing machines. 60

The machine to which the invention is shown applied, comprises the frame 1 with its top 2, the fulcrum-bar 3, the keys 4, the key-levers 5 each connected by a link 6 with a type-bar 7, the swinging carriage 8 with the platen 9 carried thereby, the universal-bar 10, the rock-shaft 11, the links 12 and 13 and arm 14 connecting the universal bar with the rock-shaft, and the spring 15 acting on the rock-shaft, which will all be recognized as parts of a No. 6 Remington machine, and consequently a detailed description of these parts and their operations is unnecessary. 75

The carriage-feed mechanism acts on the rear part 16 of the carriage through the rack 17 and pinion 18. The rack is bolted to the rear part 16 of the carriage, it being movable with the carriage and in engagement with the pinion 18. The pinion is fast on a shaft 19 having bearings at its ends in a bracket 20 on the top 2 of the frame. This bracket 80 is fastened to the frame by screws 21 and 22 extending through parts of the bracket into threaded holes in the top 2. A feed-wheel 23 is also fast on the shaft 19. In bearings in this bracket is mounted another shaft 24, 85 hereinafter termed a dog-shaft, there being on it two feed-dogs 25 and 26. The dog 25 is fixed on the dog-shaft by means of a screw 27 (shown in Fig. 5) extending through the dog to the shaft, while the dog 26 is loose on the dog-shaft, but is secured to the other dog by a lost-motion connection formed by the recess 28 in the upper end of the dog 26, and the pin 29 fixed in the dog 25 and extending through this recess. Hence each dog is movable on its axis in one direction under certain conditions without imparting movement to the other. A spring 30 (Fig. 5), attached at one end to the dog 26, and at the other to the dog 25, tends to keep the dogs in the relative positions in which they are shown in 90 95 100 105

Fig. 5, the pin 29 then being in contact with that end of the recess 28 which is between the pin and the feed-wheel.

On the lower end of the dog 26 is a projection or stud 31, which extends behind a horizontal lever 32, whose fulcrum is a pin 33 fixed in the bracket 20 and top 2 of the frame. A steel-plate 34 is affixed to this lever and in this plate is an open slot 35, somewhat resembling in form a key-hole slot open at its smaller end, as appears by dotted lines in Fig. 5. The stud 31 extends through the rear or narrow part of this slot, in which it fits loosely, so when the lever is rocked to and fro on its fulcrum 33, the edges of the slot 35 act on the stud 31 and impart motion to the dog 26 towards and from the feed-wheel 23. A restoring spring 36, which pulls on the lever, is attached to a pin 37 on the lever and to a pin 38 fixed in the bracket 20. The rocking movement of the lever is limited by a stop composed of a base 39 and arms 40, the stop being fastened to the top 2 of the frame by a screw 41 passing through the base 39 into a threaded hole in the top 2. When the lever is in the position shown in Fig. 5, which is its normal position, it makes contact with the front arm 40 of the stop, and it is movable from that position into contact with the rear arm 40 of the stop. An arm 42, by which the lever is moved from its normal position, is fixed on the rock-shaft 11. This arm has at its upper end a lateral extension 43, bearing against the back of the lever 32.

The machine is provided with a common spring-drum 44 and flexible band 45, to move the carriage under the control of the feed-mechanism described.

The feed-dog 25 engages the feed-wheel 23, and the dog 26 is outside of the path of the teeth of that wheel, when the dogs are in their normal positions, or those shown in Figs. 3 and 6. Then that end of the recess 28 in the dog 26, which is between the pin 29 and the feed-wheel, is in contact with the pin 29, and the lever 32 is in the position shown in Fig. 5. With the depression of a character-key or the space-bar, the rock-shaft 11 is turned and the lever 32 is actuated by the arm 42 on the rock-shaft 11, whereupon the dog 26 is advanced by the action of the slotted plate 34 on the stud 31 into the path of the teeth of the feed-wheel 23, and the dog 25 is forced out of engagement with the feed-wheel by the action of the dog 26 on the pin 29. The feed-wheel, as soon as it is released from the dog 25, turns a very little in consequence of the action of the spring-drum on the carriage, but is instantly arrested by the dog 26. With the return-movement of the character key or space-bar, the lever 32 is restored to its normal position by the spring 36, and the dog 26 is thereupon disengaged from the feed-

wheel, while the dog 25 is advanced by the spring 30 to the feed-wheel, with which it makes contact on the outer end of a tooth, and the feed-wheel turns, driven by the carriage, until the next tooth is engaged by the dog 25, which is advanced further by the spring 30 when the former tooth ceases to obstruct its movement. Hence with each return movement of a character-key or the space-bar, the carriage travels a single letter-space.

The dog-shaft 24 is provided at its front end with a crank-arm 46, which is fast on the shaft and on which is a crank-pin 47. A stop-pin 48, fixed in the bracket 20 and projecting over the crank-arm 46, limits the upward movement of the crank-arm. Under the crank-pin 47 extends a bent lever, which is composed of the portions 49, 50 and 51, and with which the crank-pin is held in contact by the action of the spring 30 on the dog 25. The portion 49 of this lever fits in and is supported by a bearing in the bracket 20, the lever being movable on the axis of the portion 49. Near the front end of the portion 51 the lever is bent as shown at 52 and is there supported and engaged by a movable bar, which is secured underneath the front end of the lever and by means of which the lever is actuated. This actuating device or bar is preferably mounted on the carriage, as appears by Fig. 4, which shows the bar in its preferred form. The bar shown is composed of a rod 53 bent near its ends to form on it fixed arms 54, on which are inturned projections 55 and 56, parallel to the main portion of the bar and in axial alignment with each other. The bar is attached to brackets 57 by means of these projections, on which, as pivots, the bar is movable up and down with a swinging motion. The brackets 57 are fastened to the ends of the carriage, and on them are formed stops 58 that extend under the bar to limit its downward movement. An actuating finger-piece 59 is affixed to the pivot 55 of the bar. When this bar is in its normal position it rests on the stops 58, and the feed-dog 25 is then in engagement or in contact with the feed-wheel 23, unless the dog is held out of contact with the feed-wheel by the action on it of the arm 42 through the lever 32, dog 26 and pin 29 as above described. The common release-key 60, pivoted at 61 on the swinging portion of the carriage, extends under and close to the main portion 53 of this bar, when the platen is in a normal position, as it is shown in Fig. 1, and the bar is then operative by means of the release-key, but when the platen is in an elevated position, the release-key is at too great a distance from the bar, as appears by Fig. 2, to allow the bar to be operated by this means.

The carriage is released from the control 130

of the carriage-feed mechanism, when the platen is elevated, with a backward movement of the finger-piece 59, so that the carriage may then be readily moved from right to left, as well as from left to right, to bring it to a desired position with relation to a printing-point indicator or to the particular type-bar which is to be actuated. With this movement of the finger-piece the rod 53 is turned upward on its pivots 55 and 56, the lever 49, 50, 51 is actuated by the rod, the crank pin 47 is raised by the lever, the dog-shaft 24 is turned, and the feed-dog 25 is disengaged from the feed-wheel. Meanwhile, the feed-dog 26 remains disengaged from the feed-wheel, for the pin 29 on the dog 25 travels in the recess 28 without acting on the dog 26, the spring 30 yielding as the dog 25 moves backward, and the dog 26 being held still by the lever 32. Hence until the dog 25 is allowed to return to its normal position to reengage the feed-wheel, through the action on this dog of the spring 30, the carriage is free from the control of the feed-mechanism and movable either way with the hand. It is thus movable from left to right, when the dog 26 is in its normal position, although the dog 25 is in contact with the feed-wheel, for the action of the dog 25 on the feed-wheel, like that of a pawl on a ratchet-wheel, is only capable of controlling the feed-wheel when it tends to move in one direction.

When the platen is in a normal position the carriage may be released from the control of the feed-mechanism with a depression of the front end of the release-key 60, which is then operative to turn the rod 53, as it is turned with a backward movement of the finger-piece 59, and to disengage the feed-dog 25 from the feed-wheel.

The operative relation of the rod 53 to the lever on which it acts to disengage the dog 25 from the feed-wheel, is unaffected by the movements of the carriage, whether the platen is elevated or in a normal position, as the rod, although it travels with the carriage, continues to support the front end of the lever, and to be operative either with the finger-piece 59 or the release-key 60, to actuate the lever.

When the invention is embodied in a visible-writing machine, obviously the finger-piece 59 is not needed, for the release-key 60 is then constantly engaged with the rod 53, and with a movement of this key the carriage may be released from the control of the feed-dogs, just as a swinging-carriage is released when it is in a normal position. The feed-mechanism above described, with the exception of the finger-piece 59, is applicable, then, to both visible-writing and under-strike machines. If desired, a visible-writing machine may be provided with the finger-piece 59 also. It is to be observed further

that the swinging-carriage shown is also a shift-carriage, and that the release-key 60 remains in operative connection with the rod 53 whenever the platen is shifted to or from its upper-case position. As this feature of the invention is useful only in connection with a shift-carriage, and it might be utilized with the shift-carriage of a visible-writing machine, the invention is especially applicable to machines provided with carriages of this character.

The particular carriage-feed mechanism shown herein is separately described and claimed in another application filed by me March 21, 1903, and bearing the Serial No. 148,941.

Various changes may be made in the mechanism above described without avoiding the spirit of the invention.

What I claim as new and desire to secure by Letters Patent, is:—

1. In a typewriting machine, the combination of a paper-carriage, a feed-rack on the carriage, a pinion coöperative with the feed-rack, a feed-wheel, a dog-shaft and feed-dogs mounted thereon to engage the feed-wheel, the axis of the dog-shaft being parallel to that of the feed-wheel and the dog-shaft being movable on its axis to release the feed-wheel from the control of the dogs, a release-key on the carriage, and mechanism to impart motion to the dog-shaft from the release-key.

2. In a typewriting machine, the combination of a paper-carriage, a feed-rack on the carriage, a pinion coöperative with the feed-rack, a feed-wheel, a dog-shaft and feed-dogs mounted thereon to engage the feed-wheel, the axis of the dog-shaft being parallel to that of the feed-wheel and the dog-shaft having on it a crank-arm and being movable on its axis to release the feed-wheel from the control of the dogs, a release-key on the carriage, and mechanism, including a bar operative by the release-key, to impart motion to said crank-arm from the release-key.

3. In a typewriting machine, the combination of a paper-carriage, a feed-rack on the carriage, a pinion coöperative with the feed-rack, a feed-wheel, a dog-shaft and feed-dogs mounted thereon to engage the feed-wheel, the dog-shaft having on it a crank and being movable on its axis to release the feed-wheel from the control of the dogs, a lever to act on the crank-pin of said crank, a release-key on the carriage, and a bar, operative by the release-key, to impart motion to said lever from the release-key.

4. In a typewriting machine, the combination of a paper carriage, a feed-rack on the carriage, a pinion coöperative with the feed-rack, a feed-wheel, a dog-shaft and feed-dogs mounted thereon to engage the feed-wheel, the axis of the dog shaft being paral-

lel to that of the feed-wheel and the dog-shaft being movable on its axis to release the feed-wheel from the control of the dogs, a release-key on the carriage, and mechanism, 5 including a bar mounted on the carriage and operative by the release-key, to impart motion to the dog-shaft from the release-key.

5. In a typewriting machine, the combination of a paper-carriage, a feed-rack on the 10 carriage, a pinion co-operative with the feed-rack, a feed-wheel, a dog-shaft, feed-dogs on the dog-shaft to engage the feed-wheel, one of these dogs being fast and the other loose on the dog-shaft, and they being secured together with a lost-motion connection, mechanism 15 to actuate one of the feed-dogs, and other mechanism, including a release-key on the carriage, to turn the dog-shaft and the other feed-dog with a movement of the release-key.

6. In a typewriting machine, carriage-feed mechanism comprising the combination of a feed-wheel, a dog-shaft, feed-dogs on the dog-shaft to engage the feed-wheel, one of 25 these dogs being fast and the other loose on the dog-shaft and the loose dog having on it a projection, and the dogs being secured together with a lost-motion connection, a lever engaging said projection to actuate the loose 30 feed-dog, mechanism to actuate said lever, and other mechanism, including a release-key on the carriage, to turn the dog-shaft and the other feed-dog with a movement of the release-key.

35 7. In a typewriting machine, carriage-feed mechanism comprising the combination of a feed-wheel, a dog-shaft, feed-dogs on the dog-shaft to engage the feed-wheel, one of these dogs being fast and the other loose on 40 the dog-shaft and the loose dog having on it a projection, and the dogs being secured together with a lost-motion connection, a lever engaging said projection to actuate the loose feed-dog, an arm fixed on a rock-shaft 45 and movable thereby to actuate said lever, and other mechanism, including a release-key on the carriage, to turn the dog-shaft and the other feed-dog with a movement of the release-key.

50 8. In a typewriting machine, carriage-feed mechanism comprising the combination of a feed-wheel, a dog-shaft, feed-dogs on the dog-shaft to engage the feed-wheel, one of these dogs being fast and the other loose on 55 the dog-shaft and the loose dog having on it a projection, and the dogs being secured together with a lost-motion connection, a lever including a slotted device engaging said projection to actuate the loose feed-dog, 60 mechanism to actuate said lever, and other mechanism, including a release-key on the carriage, to turn the dog-shaft and the other feed-dog with a movement of the release-key.

65 9. In a typewriting machine, carriage-feed

mechanism comprising the combination of a feed-wheel, feed-dogs to engage the feed-wheel, the dogs being movable separately and together towards and from the axis of the feed-wheel and being secured together with a lost-motion connection, mechanism to 70 actuate one of the feed-dogs, and other mechanism including a release-key on the carriage, to actuate the other feed-dog with a movement of the release-key. 75

10. In a typewriting machine, carriage-feed mechanism comprising the combination of a feed-wheel, feed-dogs to engage the feed-wheel, the dogs being movable separately and together towards and from the 80 axis of the feed-wheel and being secured together with a lost-motion connection and one of said dogs having on it a projection, a dog-actuating lever engaging said projection, mechanism to actuate said lever, and 85 other mechanism, including a release-key on the carriage, to turn the dog-shaft and the other feed-dog with a movement of the release-key.

11. In a typewriting machine, carriage-feed mechanism comprising the combination of a feed-wheel, feed-dogs to engage the feed-wheel, the dogs being movable separately and together towards and from the axis of the feed-wheel and being secured together with a lost-motion connection, a lever 90 to actuate one of said feed-dogs, a stop to limit the movements of said lever, mechanism to actuate said lever, and other mechanism, including a release-key on the carriage, 95 to turn the dog-shaft and the other feed-dog with a movement of the release-key. 100

12. In a typewriting machine, carriage-feed mechanism comprising the combination of a feed-wheel, feed-dogs to engage the 105 feed-wheel, the dogs being movable separately and together towards and from the axis of the feed-wheel and being secured together with a lost-motion connection, a lever to actuate one of said feed-dogs, a stop to 110 limit the movements of said lever, an arm fixed on a rock-shaft and movable thereby to actuate said lever, and mechanism, including a release-key on the carriage, to turn 115 the dog-shaft and the other feed-dog with a movement of the release-key.

13. In a typewriting machine, carriage-feed mechanism comprising the combination of a feed-wheel, feed-dogs to engage the feed-wheel, the dogs being movable separately and together towards and from the axis of the feed-wheel and being secured together with a lost-motion connection and one of said dogs having on it a projection, a 120 dog-actuating lever including a slotted device engaging said projection, mechanism to actuate said lever, and other mechanism, including a release-key on the carriage, to turn 125 the dog-shaft and the other feed-dog with a movement of the release-key. 130

14. In a typewriting machine, the combination of a swinging paper-carriage, carriage-feed mechanism comprising a rack with a coöperative pinion and feed-devices to control the movements of the pinion, a release-key on the carriage, a bar having arms fixed thereon and pivotally secured to supports, and mechanism operative by means of said bar when the platen is in an elevated position, to free the pinion from the control of the feed-devices, said release-key being movable into operative relation with said bar when the carriage is swung to a normal position. 5
15. 15. In a typewriting machine, the combination of a swinging paper-carriage, carriage-feed mechanism comprising a rack with a coöperative pinion and feed-devices to control the movements of the pinion, a release-key on the carriage, an actuating device mounted on the carriage, and mechanism operative by means of said actuating device when the platen is in an elevated position, to free the pinion from the control of the feed-devices, said actuating device being operative by means of said release-key when the platen is in a normal position. 10
16. In a typewriting machine, the combination of a swinging paper-carriage, carriage-feed mechanism comprising a rack with a coöperative pinion and feed-devices to control the movements of the pinion, a release-key on the carriage, a bar mounted on the carriage and movable with a swinging motion, and mechanism operative by means of said bar when the platen is in an elevated position, to free the pinion from the control of the feed-devices, said release-key being movable into operative relation 20 with said bar when the carriage is swung to a normal position. 25
17. In a typewriting machine, the combination of a swinging paper-carriage, carriage-feed mechanism comprising a rack with a coöperative pinion and feed-devices to control the movements of the pinion, a release-key on the carriage, a bar having arms fixed thereon and pivotally secured to supports on and at the ends of the carriage, and mechanism operative by means of said bar when the platen is in an elevated position, to free the pinion from the control of the feed-devices, said release-key being movable into operative relation with said bar when 30 the carriage is swung to a normal position. 35
18. In a typewriting machine, the combination of a swinging paper-carriage, a feed-rack with a coöperative pinion, a feed-wheel and feed-dogs to engage therewith to control the movements of the pinion, a release-key on the carriage, a movable bar, and mechanism operative by means of the bar when the platen is in an elevated position, to release the feed-wheel from the control of the dogs, said release-key being movable into 40
- operative relation with said bar when the carriage is swung to a normal position. 45
19. In a typewriting machine, the combination of a swinging paper-carriage, a feed-rack with a coöperative pinion, a feed-wheel, feed-dogs to engage the wheel, a dog-shaft, and mechanism operative by hand to turn the dog-shaft when the platen is in an elevated position, to release the feed-wheel from the control of the dogs. 70 75
20. In a typewriting machine, the combination of a swinging paper-carriage, a feed-rack with a coöperative pinion, a feed-wheel, feed-dogs to engage the wheel, a dog-shaft provided with a crank-arm, and mechanism to actuate the crank-arm when the platen is in an elevated position, to release the feed-wheel from the control of the dogs. 80
21. In a typewriting machine, the combination of a swinging paper-carriage, a feed-rack with a coöperative pinion, a feed-wheel, a dog-shaft, feed-dogs to engage the feed-wheel, one dog being fast and the other loose on the shaft, and they being secured together by a lost-motion connection, and mechanism operated by hand to turn the dog-shaft when the platen is in an elevated position, to release the feed-wheel from the control of the dogs. 85 90
22. In a typewriting machine, the combination of a swinging paper-carriage, a feed-rack with a coöperative pinion, a feed-wheel, feed-dogs to engage the wheel, a dog-shaft mounted in fixed bearings, the axis of the dog-shaft being parallel to that of the feed wheel, and mechanism comprising a device mounted on the carriage and movable by hand to turn the dog-shaft when the platen is in an elevated position, to release the feed-wheel from the control of the dogs. 95 100 105
23. In a typewriting machine, the combination of a swinging paper-carriage, a feed-rack with a coöperative pinion, a feed-wheel, feed-dogs to engage the wheel, a dog-shaft provided with a crank-arm, and mechanism comprising a bar mounted on the carriage and movable to actuate the crank-arm when the platen is in an elevated position, to release the feed-wheel from the control of the dogs. 110 115
24. In a typewriting machine, the combination of a swinging paper-carriage, a feed-rack with a coöperative pinion, a feed-wheel, a dog-shaft, feed-dogs to engage the feed-wheel, one dog being fast and the other loose on the shaft, and they being secured together by a lost-motion connection, and mechanism comprising a bar mounted on the carriage and movable to turn the dog-shaft when the platen is in an elevated position, to release the feed-wheel from the control of the dogs. 120 125
25. In a typewriting machine, the combination of a swinging paper-carriage, a feed-rack with a coöperative pinion, a feed-wheel, feed-dogs to engage the wheel, a dog-shaft 130

provided with a crank-arm, a lever to actuate the crank-arm, and a device to actuate the lever when the platen is in an elevated position, to release the feed-wheel from the 5 control of the dogs.

26. In a typewriting machine, the combination of a swinging paper-carriage, a feed-rack with a coöperative pinion, a feed-wheel, feed-dogs to engage the wheel, a dog-shaft 10 provided with a crank-arm, a lever to actuate the crank-arm, and a device mounted on the carriage and movable to actuate the lever when the platen is in an elevated position, to release the feed-wheel from the control of 15 the dogs.

27. In a typewriting machine, the combination of a swinging paper-carriage, a feed-rack with a coöperative pinion, a feed-wheel, feed-dogs to engage the wheel, a dog-shaft 20 provided with a crank-arm, a lever to actuate the crank-arm, and a bar engaged with the lever in a relation that is unaffected by the movements of the carriage, said bar being movable to actuate the lever when the 25 platen is in an elevated position, to release the feed-wheel from the control of the dogs.

28. In a typewriting machine, the combination of a swinging paper-carriage, a feed-

rack with a coöperative pinion, a feed-wheel, feed-dogs to engage the wheel, a dog-shaft 30 provided with a crank-arm, a lever to actuate the crank-arm, and a bar mounted on the carriage and engaged with the lever in a relation that is unaffected by the movements of the carriage, said bar being movable to 35 actuate the lever when the platen is in an elevated position, to release the feed-wheel from the control of the dogs.

29. In a typewriting machine, the combination of a paper carriage, a feed rack on the 40 carriage, a pinion coöperating with the feed rack, a feed wheel and feed dogs to engage therewith to control the movements of the pinion, a dog shaft on which one of said feed dogs is fast, a release key on the carriage, a 45 bar movable by the release key, and a device operative by said bar to turn the dog shaft.

Signed at the borough of Manhattan, city of New York, in the county of New York, and State of New York, this 20th day of 50 March, A. D. 1903.

WILLIAM C. FARNUM.
